TOY HORIZONTAL BAR

Kosei Kato, Tokyo, Japan, assignor to
Tomy Kogyo Co., Inc., Tokyo, Japan

Filed Apr. 5, 1974, Ser. No. 458,194

Term of patent 14 years

Int. Cl. D21—01

U.S. Cl. D34—15 R

FIG. 1

FIG. 2

FIG. 3

FIG. 4

FIG. 5

FIG. 6

FIG. 1 is a perspective view of a toy horizontal bar showing my new design;

FIG. 2 is a rear elevational view thereof;

FIG. 3 is a left side elevational view thereof;

FIG. 4 is a top plan view thereof;

FIG. 5 is a right side elevational view thereof; and

FIG. 6 is a bottom plan view thereof.

I claim:

The ornamental design for a toy horizontal bar, as shown and described.
